UNITED STATES PATENT OFFICE.

THOMAS W. HARDING, OF TUNSTALL, ENGLAND, ASSIGNOR TO HUGH C. EDMISTON,
OF NEW YORK, N. Y.

DESIGN FOR A COVERED DISH OR SIMILAR ARTICLE.

Application filed December 1, 1928, Serial No. 29,085, and in Great Britain November 9, 1928.
Term of Patent 7 years.

To all whom it may concern:

Be it known that I, THOMAS WM. HARDING, a subject of the King of Great Britain, residing at Tunstall, county of Stafford, England, have invented a new, original, and ornamental Design for a Covered Dish or Similar Article, of which the following is a specification, reference being had to the accompanying drawing, forming part thereof.

I claim:

The ornamental design for a covered dish or similar article as shown.

THOMAS WM. HARDING.
